WHEELBARROW NOSE PIECE

Roger R. Tonelli, 1708 N. Oak Park Ave., Chicago, Ill.

Filed June 22, 1965, Ser. No. 85,854

Term of patent 14 years

(Cl. D14—3)

FIG. 1

FIG. 2

FIG. 3

FIG. 4

FIG. 5

FIG. 6

FIG. 1 is a perspective view of the wheelbarrow nose piece embodying my new design. The fragmentary portion of a wheelbarrow shown in broken lines in FIG. 1 is included for illustrative purposes only.

FIG. 2 is a top plan view thereof with a portion cut away for an interior view thereof;

FIG. 3 is a front elevational view thereof;

FIG. 4 is a back elevational view thereof;

FIG. 5 is an end elevational view thereof; and

FIG. 6 is a sectional elevational view of the end section shown in FIG. 5.

I claim:

The ornamental design for a wheelbarrow nose piece, as shown and described.
